UNITED STATES PATENT OFFICE.

CHARLES A. ROBINSON, OF OKLAHOMA, OKLAHOMA.

MACHINE FOR TREATING LUMBER.

1,237,558.

Specification of Letters Patent. Patented Aug. 21, 1917.

Application filed March 3, 1917. Serial No. 152,338.

To all whom it may concern:

Be it known that I, CHARLES A. ROBINSON, a citizen of the United States, residing at Oklahoma city, in the county of Oklahoma and State of Oklahoma, have invented a new and useful Machine for Treating Lumber, of which the following is a specification.

The device forming the subject matter of this application is adapted to be employed for treating lumber, and the invention aims to provide novel means whereby the wood may be advanced, and be dried as it is advanced, a preserving liquid being applied to the wood, after it has been dried, and the surplus liquid being blown off the wood, before the wood is delivered, means being provided for conducting away the surplus preserving liquid.

To embody in an efficient working machine the features above mentioned is, broadly speaking, the object of the invention.

The invention aims, further, to improve and enhance the utility of devices of that general type hereinafter described.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:

Figure 1 shows in side elevation, a machine for treating timber, constructed in accordance with the present invention, parts being broken away;

Fig. 2 is a top plan of a machine of the sort hereinafter described, the figure being separated into two parts showing the respective ends of the machine, in order that the parts may appear on a sufficiently large scale;

Fig. 3 is a cross section taken approximately on the line 3—3 of Fig. 1;

Fig. 4 is a cross section taken approximately on the line 4—4 of Fig. 1;

Fig. 5 is a fragmental perspective showing a portion of the conveyer; and

Fig. 6 is a fragmental top plan, parts being broken away in order that the connections between one of the headers and adjoining pipes may appear clearly.

In carrying out the present invention there is provided a supporting structure which may be variously constructed without jeopardizing the utility of the device. In the present instance, but not of necessity, the supporting structure includes base beams 1 from which rise posts 2. That end of the machine to which the reference letter A has been applied in Fig. 1, will be denominated the forward end of the machine, the rear end of the machine being denoted by the reference letter B. Disposed at the forward end of the machine are side plates 3 supporting a feed table 4. Arranged at the rear end of the machine are side plates 5 supporting a delivery table 6. A drive shaft 7 is journaled in the side plates 3 and carries sprocket wheels 8. A drive shaft 9 is journaled in the side plates 5 and carries sprocket wheels 10. The side plates 5 support a shaft 11 carrying sprocket wheels 12. The numeral 14 marks a shaft having sprocket wheels 15, the shaft 14 being carried by slide bearings 16 supported on the side plates 3. The numeral 17 denotes any suitable mechanism, whereby the slide bearings 16 may be moved longitudinally of the machine. Mounted on the base beams 1 are brackets 18 carrying wheels 19. Extended along the sides of the machine and carried by the posts 2 are supports 20 in the form of angle bars. The device includes a belt conveyer 21, the links of which are pivotally connected together as shown at 22. At intervals, the side chains which make up the belt conveyer 21 are united by spacing rods 23 which may form pivotal connections between certain of the links of the chains. Certain of the links of the constituent chains of the conveyer 21 are provided with upstanding fingers 50. The upper run of the chains of the conveyer slide along the horizontal flanges of the angle bar supports 20, the chains being held apart by the rods 23, so that the chains will ride along the horizontal flanges of the supports 20 as aforesaid. The upper runs of the chains of the belt conveyer engage the driving sprocket wheels 10 and 8 when passed around the sprocket wheels 12 and 15. The lower runs of the constituent chains of the belt conveyer are supported on the wheels 19, the wheels 19 being spaced from the posts 1 as clearly shown in Fig. 3, to the end that the fingers 50 on the chains of the belt conveyer may pass between the wheels and the posts.

The belt conveyer may be tightened up by shifting the slide bearings 16 by the mechanisms indicated at 17.

Disposed intermediate the forward and rear ends of the machine is a transverse header 24 having, as shown in Fig. 3, a partition 25 which extends longitudinally of the machine and divides the header into separate compartments. The numeral 26 indicates a plurality of U-shaped upper pipes, the forward ends of which are connected with the header 24. One end of each pipe 26 communicates with the header on one side of the partition 25, and the other end of each pipe communicates with the header on the other side of the partition 25, so that the proper circulation of steam through the pipes may be secured. The pipes 26 are in a common horizontal plane, one pipe being disposed within the space defined by the side arms of the next adjoining pipe. The pipes 26 may be supported on the cross bar 27, connecting the posts 2. From the header 24, a pipe 28 extends longitudinally of the machine to a transverse feed pipe 29, whereby steam is supplied. From the header 24, a pipe 30 extends longitudinally of the machine to a steam return pipe 31. The pipes 30 and 28 open into the header 24 on opposite sides of the partition 25.

Disposed relatively near to the forward end of the machine is a transverse header 32, which is constructed like the header 24. Rearwardly extended U-shaped pipes 33 open into the header 32 and extend rearwardly beyond the header 24. The pipes 33 are disposed at a lower level than are the pipes 26. The pipes 33 are supported on a cross bar 34 connecting certain of the posts 2. From the header 32, a pipe 35 leads to the return pipe 31; a pipe 36 forming a connection between the header 32 and the pipe 29.

Disposed adjacent the rear end of the machine is an air blast pipe 37 having a depending arm 38 connected with a pipe 39 which extends longitudinally of the device. The pipe 39 is provided with transverse nozzles 40 having perforations 41 on their under sides. The numeral 42 has been used to designate a pipe whereby a preserving liquid is supplied to the timber, the pipe 42 having a depending arm 43 connected with a pipe 44 extended longitudinally of the machine, the pipe 44 carrying transverse perforated nozzles 45 like the nozzles 40.

Disposed below the nozzles 40 and 45 and between the upper and lower runs of the belt conveyer 21 is a receptacle or pan 46 having an outlet 47 communicating with a transverse drain pipe 48 as shown in Fig. 4.

The numeral 49 denotes an overhead support carrying depending hangers 51 on

which are journaled shafts 52 connected with flexible elements 53 united with the upper edges of panels 54, the ends of which move in closed relation to each other. The shafts 52 are actuated by gear trains 55 carried by posts 57 and driven by cranks 56 or in any other suitable way.

Noting the point at which the reference character 58 is applied in Fig. 2, it will be understood that the structure above described may be duplicated to any desired extent, that is, the machine may consist of any desired number of units like the one hereinbefore set forth, these units being disposed side by side, in order that timber of any length may be treated.

The operation of the device is as follows:

Presupposing that the belt conveyer 21 is in motion, the timber is placed on the feed table 4 and is advanced manually until it is picked up by the fingers 50 of the belt conveyer. The timber is then advanced over the single bank of pipes 33 which project from the header 32 and lie in advance of the header 24. Ultimately, the timber is advanced until it is above the pipes 26 which project from the header 24 and also above those portions of the pipes 33 which lie beneath the pipes 26. In this way, the heat applied to the timber is increased.

The timber then travels through the field of the nozzle 45, and a preserving liquid, supplied through the pipe 42, is applied to the timber. The timber then passes within the field of the air blast nozzles 40, and the surplus preserving liquid on the timber is blown off. Any preserving liquid which may drop from the timber while the timber is beneath the nozzles 45 or the nozzles 41 is received by the pan 46 and is conducted away through the outlet 47 and the drain pipe 48. Finally, the timber is advanced by the fingers 50 on the belt conveyer 21, onto the delivery table 6.

Steam is supplied from the pipe 29 and the pipe 28 to the header 24 and thence to the intake ends of the U-shaped pipes 26, the steam being returned from the header 24, by way of the pipe 30 and the pipe 31. In a similar way, steam is supplied from the pipe 29 and the pipe 36 to the header 32 and the U-shaped pipes 33, the steam being returned from the header 32 by way of the pipe 35 and the pipe 31.

If comparatively short lengths of timber, such as shooks or shingles are to be treated, then the panels 54 are lowered by rotating the shafts 52 through the instrumentality of the gear trains 55. In this way, the heat is confined to a single unit of the machine. It is possible, however, to raise one or more sets of the panels 54, so that longer pieces of timber may be treated, two or more units being employed, it being recalled, as indi-

cated at 58, that it is contemplated that the machine described may be duplicated to any desired extent, depending on the length of the material to be treated.

5 Having thus described the invention, what is claimed is:—

1. In a machine for treating lumber, a supporting structure; a belt conveyer mounted to traverse the supporting structure; a heater located within the contour of the belt conveyer adjacent the forward end of the supporting structure; a liquid applying means operating above the belt conveyer at the rear of the heater; and a blast device operating above the conveyer to the rear of the liquid applying means.

2. In a machine for treating lumber, a supporting structure; a belt conveyer traversing the supporting structure; a heater located within the contour of the belt conveyer and disposed adjacent the forward end of the supporting structure; an air blast mechanism operating above the conveyer at the rear end of the supporting structure; a liquid applying means operating above the belt conveyer between the heater and the air blast mechanism; a receptacle extended beneath the air blast mechanism and the liquid applying means; 30 and a drain conduit wherewith the receptacle communicates.

3. In a machine for treating lumber, a supporting structure; a belt conveyer mounted to traverse the supporting structure; a heater located within the contour of the belt conveyer adjacent the forward end of the supporting structure; an air blast mechanism operating above the belt conveyer at the rear end of the supporting structure; a liquid applying means operating above the belt conveyer between the heater and the air blast mechanism; vertically movable closures disposed on opposite sides of the belt conveyer; and means for 45 raising and lowering the closures.

4. In a machine for treating lumber, a supporting structure; a conveyer traversing the supporting structure; a heater arranged adjacent the forward end of the device and located below a part of the conveyer; an air blast mechanism operating above the conveyer and disposed at the rear end of the device; a liquid applying means operating above the conveyer and disposed between 55 the heater and the air blast mechanism; a receptacle located below the air blast mechanism and liquid applying means and below said portion of the conveyer; closures vertically movable at the sides of the conveyer;

and means for raising and lowering the 60 closures.

5. In a machine for treating lumber, a supporting structure; a main transverse header located between the ends of the supporting structure; rearwardly extended U- 65 shaped pipes connected with the main header; a secondary header located adjacent the forward end of the device; U-shaped pipes connected with the auxiliary header and extending throughout a portion of their 70 lengths beneath the first specified U-shaped pipes; a conveyer traversing the supporting structure above the pipes; means for applying liquid to the material on the conveyer, to the rear of the pipes; and means 75 for applying an air blast to the material on the conveyer, to the rear of the means for applying liquid.

6. In a machine for treating lumber, a supporting structure; a header disposed 80 transversely of the supporting structure and located intermediate the ends of the supporting structure; a second header arranged adjacent the forward end of the supporting structure; U-shaped pipes of different 85 lengths connected with the respective headers and disposed on different elevations; means for supplying heat to the respective headers; a conveyer mounted to move above the pipes and the headers; means for discharging liquid onto the material on the conveyer, to the rear of the pipes; a receptacle disposed below the working portion of the conveyer and below said means; and vertically movable closures operating at the 95 sides of the conveyer.

7. A machine for treating lumber embodying means for advancing the material to be treated; means for applying liquid to the material as it is being advanced; means 100 for heating the material before the liquid is applied thereto; and a mechanism for applying an air blast to the material after the liquid has been applied thereto.

8. A machine for treating lumber embodying means for advancing the material to be treated; means for applying liquid to the material as it is being advanced; and means for heating the material while the material is being advanced and before the 110 liquid is applied thereto.

In testimony that I claim the foregoing as my own, I have hereto affixed my signature in the presence of two witnesses.

CHARLES A. ROBINSON.
